UNITED STATES PATENT OFFICE.

HERBERT A. BURCH, OF KALAMAZOO, MICHIGAN.

CARBURETER.

No. 820,036.

Specification of Letters Patent.

Patented May 8, 1906.

Application filed March 25, 1905. Serial No. 261,985.

To all whom it may concern:

Be it known that I, HERBERT A. BURCH, a citizen of the United States, and a resident of the city and county of Kalamazoo, State of Michigan, have invented certain new and useful Improvements in Carbureters, of which the following is a specification.

This invention relates to improvements in carbureters.

- 10 The objects of this invention are, first, to provide an improved carbureter by which a comparatively even grade of carbureted air or gas may be produced without regard to the quantity; second, to provide an improved carbureter in which all of the liquid hydrocarbon is utilized; third, to provide an improved carbureter in which low grades of refined hydrocarbon-oils can be used with satisfactory results; fourth, to provide an improved carbureter which although very simple and compact in structure is of large capacity; fifth, to provide an improved carbureter which is simple in structure, economical to produce, and one which is very durable
- 15 and not likely to get out of repair.
- 20
- 25

Further objects and objects relating to structural details will definitely appear from the detailed description to follow.

I accomplish the objects of my invention

30 by the devices and means described in the following specification.

The invention is clearly defined and pointed out in the claims.

A structure embodying the features of my invention is clearly illustrated in the accompanying drawings, forming a part of this specification, in which—

Figure 1 is a vertical longitudinal sectional view through my improved carbureter, 40 taken on a line corresponding to line 1 1 of Fig. 2. Fig. 2 is a detail transverse vertical section taken on a line corresponding to line 2 2 of Fig. 1. Fig. 3 is a plan view of one of the carbureting-screens, the screen being partially removed from the frame to show the structural arrangement thereof. Fig. 4 is an enlarged detail inverted plan showing structural details of the trough a. Fig. 5 is an enlarged detail view showing one of the 50 carbureting device holders B in position in the carbureter-chamber. Fig. 6 is a detail sectional view taken on line 6 6 of Fig. 5. Fig. 7 is a detail view showing a modification, the carbureting devices B being arranged in a vertical position.

In the drawings the sectional views are taken looking in the direction of the little arrows at the ends of the section-lines, and similar letters of reference refer to similar parts throughout the several views.

60

Referring to the drawings, the carbureter-chambers A are preferably rectangular in form and are arranged in a horizontal position. These chambers are preferably arranged in series, one above another, as 65 clearly appears in Fig. 1. The chambers are connected, as will be fully described later herein. In the top of each chamber is an oil-delivery trough a. These troughs are preferably formed by striking up portions of the 70 covers of the carbureter-chambers and soldering a bottom plate over the same, as clearly appears in Figs. 2 and 4. These troughs a extend longitudinally of the chambers and are provided with a plurality of 75 delivery-openings o. The delivery-openings o' at the ends of the trough are considerably larger than the delivery-openings o to allow the ready escape of any surplus oil.

The liquid hydrocarbon is delivered by the 80 delivery-pipe A' to the trough a of the upper or top carbureter-chamber. The pipe A' is arranged to deliver to the trough a at a central point. The liquid hydrocarbon is delivered from the upper carbureter-chamber to 85 the delivery-troughs of the carbureter-chambers below by pipes or conduits a'. These pipes a' project upwardly into the chambers a short distance to determine the level of the liquid hydrocarbon therein, as clearly appears from Fig. 1. The carbureter-chambers are also connected by air-pipes a''. These pipes connect the rear end of each chamber with the forward end of the chamber next above or next in the series. The 90 carbureter-chambers are arranged in alternate relation to each other, so that air passing through them takes a zigzag course through the series. The upper ends of these air-connecting pipes a'' project above the upper ends of the oil-delivery conduits a', so that it is impossible for the liquid hydrocarbon to pass therethrough.

A plurality of carbureting devices B are arranged in series in each carbureting-chamber. 105 These carbureting devices consist of frames b, to which carbureting-screens B' are secured. These screens B' are preferably made of some loosely-woven textile fabric, coarse linen being preferred by me. The car- 110

bureting devices B are preferably arranged in a forwardly-inclined position, as is illustrated in Figs. 1 and 4, and form a series of complete partitions across the carbureter-chambers. These carbureting devices are supported by holders B'', into which they may be slipped. These holders are arranged oppositely on the side walls of the carbureter-chambers. (See Figs. 2, 5, and 6.)

10 The bottoms of the carbureting devices rest on the bottoms of the carbureter-chambers or at least extend below the plane of the top of the conduits a', so that they extend into the liquid hydrocarbon. Interposed between the tops of the carbureting devices and the tops of the carbureter-chambers are layers of fabric b'', which serve as conveyers or distributors for the liquid hydrocarbon delivered from the troughs a. The liquid hydrocarbon is thus first delivered to the upper edges of the carbureting-screens and by gravity and also by capillarity soon spreads over the same. When the screens are saturated, the surplus is delivered to the bottom of the carbureter-chambers, and it is intended that the bottoms of the chambers shall at all times be covered by the liquid hydrocarbon to a slight depth, preferably about one-quarter of an inch. The liquid hydrocarbon is also carried up by capillarity from the bottom of the carbureter-chambers, so that the carbureting-screens are kept thoroughly saturated at all times, as this fresh supply is delivered to the upper end of the same in quantities sufficient to compensate for that which is taken up by the air passing through the carbureter.

15 The air is delivered to the forward end of the lower carbureter-chamber by the air-supply pipe C and is forced through the carbureting devices of the lower carbureter-chamber to the pipe a'', through which it is delivered to the forward end of the second carbureter-chamber, through which it passes to the top carbureter-chamber and is delivered from the rear end thereof by the gas-supply pipe C'.

20 The air passing through the carbureter-chambers is brought into contact with the liquid hydrocarbon which is held by the carbureting-screens B' of the carbureting devices, so that it is very effectively charged. As the screens are at all times saturated, the quality of the gas remains comparatively constant no matter what quantity may be used. The quality of the gas or carbureted air is also good from the first starting of the carbureter.

25 The screens B' are tightly stretched upon the frames b and are preferably secured thereon by sewing. Cross-pieces b' are provided for the frame b to prevent the sagging of the screens and also to make the frame rigid. By thus constructing the same it can be made of comparatively light wire. By arranging the troughs a as I have illustrated the oil is delivered to the distributors b'' at intervals along

the same. The oil is carried by these distributors by capillarity, so that it is distributed to the upper ends of the carbureting devices upon which it rests. As the edges of the carbureting-screens B' are wrapped over 70 the frame they are brought into perfect contact with the distributors b'', so that the liquid hydrocarbon is delivered thereto by capillarity.

30 I preferably arrange the carbureting devices B in a forwardly-inclined position, as is clearly illustrated in Fig. 1. Desirable results may, however, be secured by arranging them in a vertical position, as is illustrated in the modified construction shown in Fig. 7. 80 In order to secure satisfactory results, it is desirable, however, that they should form complete partitions from the top to the bottom of the chambers—that is, that they should extend into the liquid hydrocarbon in 85 the base of the carbureter-chambers and be positioned to receive the oil at their upper edges.

35 With the parts arranged as I have illustrated and described the carbureting devices 90 present a minimum amount of obstruction to the passage of the air, so that only a small amount of pressure is required to force the air therethrough. I am enabled by my improved carbureter to use the lower grades of 95 hydrocarbon-oil and secure practical results and to utilize practically all of the same. My improved carbureter is very economical to produce and is compact and simple in structure, and the device is of very large capacity 100 in proportion to its size.

40 I have illustrated and described my improved carbureter in detail in the form preferred by me on account of its structural simplicity and economy. I am, however, aware 105 that it is capable of considerable variation in structural details without departing from my invention.

45 I claim—

1. The combination of a plurality of carbureter-chambers, arranged in a horizontal position, one above another; liquid-hydrocarbon-delivery troughs having a plurality of delivery-openings therein, arranged in the tops of said chambers; a liquid-hydrocarbon-supply pipe adapted to deliver to the delivery-trough of the upper carbureter-chamber; a pipe extending upwardly into the upper carbureter-chamber opening into the delivery-trough of the carbureter-chamber next 110 below; an air-pipe connecting the rear end of the lower carbureter-chamber to the forward end of the chamber next above; a plurality of carbureting devices consisting of frames having carbureting-screens of textile fabric 115 secured thereon; U-shaped holders for said carbureting devices arranged in pairs in a forwardly-inclined position on the side walls of said carbureter-chambers; and distributors 120 of textile fabric adapted to receive the liquid 125 secured thereon; U-shaped holders for said carbureting devices arranged in pairs in a forwardly-inclined position on the side walls of said carbureter-chambers; and distributors 130 of textile fabric adapted to receive the liquid

from said delivery-troughs resting upon the upper edges of said carbureting devices, for the purpose specified.

2. The combination of a plurality of carbureter-chambers, arranged in a horizontal position, one above another; liquid-hydrocarbon-delivery troughs having a plurality of delivery-openings therein, arranged in the tops of said chambers; a liquid-hydrocarbon-supply pipe adapted to deliver to the delivery-trough of the upper carbureter-chamber; a pipe extending upwardly into the upper carbureter-chamber opening into the delivery-trough of the carbureter-chamber next below; an air-pipe connecting the rear end of the lower carbureter-chamber to the forward end of the chamber next above; a plurality of carbureting devices consisting of frames having carbureting-screens of textile fabric secured thereon; U-shaped holders for said carbureting devices arranged in pairs on the side walls of said carbureter-chambers; and distributers of textile fabric adapted to receive the liquid from said delivery-troughs resting upon the upper edges of said carbureting devices, for the purpose specified.

3. The combination of a plurality of carbureter-chambers, arranged in a horizontal position, one above another; liquid-hydrocarbon-delivery troughs having a plurality of delivery-openings therein, arranged in the tops of said chambers; a liquid-hydrocarbon-supply pipe adapted to deliver to the delivery-trough of the upper carbureter-chamber; a pipe extending upwardly into the upper carbureter-chamber opening into the delivery-trough of the carbureter-chamber next below; an air-pipe connecting the rear end of the lower carbureter-chamber to the forward end of the chamber next above; a plurality of carbureting devices, consisting of frames having carbureting-screens of textile fabric secured thereon; and U-shaped holders for said carbureting devices arranged in pairs in a forwardly-inclined position on the side walls of said carbureter-chambers, for the purpose specified.

4. The combination of a plurality of carbureter-chambers, arranged in a horizontal position, one above another; liquid-hydrocarbon-delivery troughs having a plurality of delivery-openings therein, arranged in the tops of said chambers; a liquid-hydrocarbon-supply pipe adapted to deliver to the delivery-trough of the upper carbureter-chamber; a pipe extending upwardly into the upper carbureter-chamber opening into the delivery-trough of the carbureter-chamber next below; an air-pipe connecting the rear end of the lower carbureter-chamber to the forward end of the chamber next above; a plurality of carbureting devices consisting of frames having carbureting-screens of textile fabric secured thereon; and U-shaped holders for said carbureting devices arranged in pairs on the

side walls of said carbureter-chambers, for the purpose specified.

5. The combination of a plurality of carbureter-chambers, arranged in a horizontal position, one above another; liquid-hydrocarbon-delivery troughs having a plurality of delivery-openings therein, arranged in the tops of said chambers; a liquid-hydrocarbon-supply pipe adapted to deliver to the delivery-trough of the upper carbureter-chamber; a pipe extending upwardly into the upper carbureter-chamber opening into the delivery-trough of the carbureter-chamber next below; an air-pipe connecting the rear end of the lower carbureter-chamber to the forward end of the chamber next above; a plurality of carbureting devices having carbureting-screens of textile fabric; U-shaped holders for said carbureting devices arranged in pairs in a forwardly-inclined position on the side walls of said carbureter-chambers; and distributers of textile fabric adapted to receive liquid from said delivery-troughs resting upon the upper edges of said carbureting devices, for the purpose specified.

6. The combination of a plurality of carbureter-chambers, arranged in a horizontal position, one above another; liquid-hydrocarbon-delivery troughs having a plurality of delivery-openings therein, arranged in the tops of said chambers; a liquid-hydrocarbon-supply pipe adapted to deliver to the delivery-trough of the upper carbureter-chamber; a pipe extending upwardly into the upper carbureter-chamber opening into the delivery-trough of the carbureter-chamber next below; an air-pipe connecting the rear end of the lower carbureter-chamber to the forward end of the chamber next above; a plurality of carbureting devices having carbureting-screens of textile fabric; U-shaped holders for said carbureting devices arranged in pairs on the side walls of said carbureter-chambers; and distributers of textile fabric adapted to receive the liquid from said delivery-troughs resting upon the upper edges of said carbureting devices, for the purpose specified.

7. The combination of a plurality of carbureter-chambers, arranged in a horizontal position, one above another; liquid-hydrocarbon-delivery troughs having a plurality of delivery-openings therein, arranged in the tops of said chambers; a liquid-hydrocarbon-supply pipe adapted to deliver to the delivery-trough of the upper carbureter-chamber; a pipe extending upwardly into the upper carbureter-chamber opening into the delivery-trough of the carbureter-chamber next below; an air-pipe connecting the rear end of the lower carbureter-chamber to the forward end of the chamber next above; a plurality of carbureting devices having carbureting-screens of textile fabric; and U-shaped holders for said carbureting devices arranged in pairs in a forwardly-inclined position on the side walls of

said carbureter-chambers; for the purpose specified.

8. The combination of a plurality of carbureter-chambers, arranged in a horizontal position, one above another; liquid-hydrocarbon-delivery troughs having a plurality of delivery-openings therein, arranged in the tops of said chambers; a liquid-hydrocarbon-supply pipe adapted to deliver to the delivery-trough of the upper carbureter-chamber; a pipe extending upwardly into the upper carbureter-chamber opening into the delivery-trough of the carbureter-chamber next below; an air-pipe connecting the rear end of the lower carbureter-chamber to the forward end of the chamber next above; and a plurality of carbureting devices consisting of frames having carbureting-screens of textile fabric secured thereon, arranged transversely in said chambers forming complete partitions therein, for the purpose specified.

10 15 20 25 30 35 40 45 50 55 60 65 70 75 80 85 90 95 100 105 110 115 120 125 130

9. The combination of a plurality of carbureter-chambers, arranged in a horizontal position, one above another; liquid-hydrocarbon-delivery troughs arranged in the tops of said chambers; a liquid-hydrocarbon-supply pipe adapted to deliver to the delivery-trough of the upper carbureter-chamber; a pipe opening into the upper carbureter-chamber and into the delivery-trough of the carbureter-chamber next below; an air-pipe connecting the rear end of the lower carbureter-chamber to the forward end of the chamber next above; a plurality of carbureting devices consisting of frames having carbureting-screens of textile fabric secured thereon, arranged transversely in said chambers and forming complete partitions therein; and distributers adapted to receive the liquid from said delivery-troughs resting upon the upper edges of said carbureting devices, for the purpose specified.

10. The combination of a plurality of carbureter-chambers, arranged in a horizontal position, one above another; liquid-hydrocarbon-delivery troughs arranged in the tops of said chambers; a liquid-hydrocarbon-supply pipe adapted to deliver to the delivery-trough of the upper carbureter-chamber; a pipe opening into the upper carbureter-chamber and into the delivery-trough of the carbureter-chamber next below; an air-pipe connecting the rear end of the lower carbureter-chamber to the forward end of the chamber next above; a plurality of carbureting devices having carbureting-screens of textile fabric arranged transversely in said chambers and forming complete partitions therein; and distributers adapted to receive the liquid from said delivery-troughs resting upon the upper edges of said carbureting devices, for the purpose specified.

11. The combination of a plurality of carbureter-chambers arranged in a horizontal position, one above another; liquid-hydro-

carbon-delivery troughs arranged in the tops of said chambers; a liquid-hydrocarbon-supply pipe adapted to deliver to the delivery-trough of the upper carbureter-chamber; a pipe opening into the upper carbureter-chamber and into the delivery-trough of the carbureter-chamber next below; an air-pipe connecting the rear end of the lower carbureter-chamber to the forward end of the chamber next above; and a plurality of carbureting devices consisting of frames having carbureting-screens of textile fabric secured thereon, arranged transversely in said chambers forming complete partitions therein, for the purpose specified.

12. The combination of a plurality of carbureter-chambers arranged in a horizontal position, one above another, liquid-hydrocarbon-delivery troughs arranged in the tops of said chambers; a liquid-hydrocarbon-supply pipe adapted to deliver to the delivery-trough of the upper carbureter-chamber; a pipe opening into the upper carbureter-chamber and into the delivery-trough of the carbureter-chamber next below; an air-pipe connecting the rear end of the lower carbureter-chamber to the forward end of the chamber next above; and a plurality of carbureting devices having carbureting-screens of textile fabric arranged transversely in said chambers and forming complete partitions therein, for the purpose specified.

13. The combination of a plurality of carbureter-chambers arranged in a horizontal position, one above another, the lower portions of said chambers being adapted to serve as liquid-reservoirs; an air-pipe connecting the rear end of the lower carbureter-chamber to the forward end of the chamber next above; a plurality of carbureting devices having carbureting-screens of textile fabric arranged transversely in said chambers and forming complete partitions therein, the said carbureting devices being arranged in forwardly-inclined positions; distributers arranged over the said carbureting devices and resting thereon; and connections for delivering the liquid hydrocarbon from the upper carbureter-chambers to the distributers of the chambers next below, for the purpose specified.

14. The combination of a plurality of carbureter-chambers arranged in a horizontal position, one above another, the lower portion of said chambers being adapted to serve as liquid-reservoirs; an air-pipe connecting the rear end of the lower carbureter-chamber with the forward end of the chamber next above; a plurality of carbureting devices having carbureting screens of textile fabric arranged transversely in said chambers and forming complete partitions therein; distributers arranged over the said carbureting devices and resting thereon; and connections for delivering the liquid hydrocarbon

from the upper carbureter-chambers to the distributors of the chambers next below, for the purpose specified.

15. The combination of a plurality of carbureter-chambers arranged in a horizontal position, one above another; an air-pipe connecting the rear end of the lower carbureter-chamber to the forward end of the next chamber above; a plurality of carbureting devices having carbureting-screens of textile fabric arranged transversely in said chambers and forming complete partitions therein, the said carbureting devices being arranged in forwardly-inclined positions; distributors arranged over the said carbureting devices and resting thereon; and connections for delivering the liquid hydrocarbon from the upper carbureter-chambers to the distributors of the chambers next below, for the purpose specified.

16. The combination of a plurality of carbureter-chambers arranged in a horizontal position, one above another; an air-pipe connecting the rear end of the lower carbureter-chamber with the forward end of the chamber next above; a plurality of carbureting devices having carbureting-screens of textile fabric arranged transversely in said chambers and forming complete partitions therein; distributors arranged over the said carbureting devices and resting thereon; and connections for delivering the liquid hydrocarbon from the upper carbureter-chambers to the distributors of the chambers next below, for the purpose specified.

17. The combination of a plurality of carbureter-chambers arranged in a horizontal position, one above another; the lower portions of said chambers being adapted to serve as liquid-reservoirs; an air-pipe connecting the rear end of the lower carbureter-chamber with the forward end of the chamber next above; a plurality of carbureting devices arranged transversely in said chambers and forming complete partitions therein; distributors arranged over the said carbureting devices and resting thereon; and connections for delivering the liquid hydrocarbon from the upper carbureter-chambers to the distributors of the chambers next below, for the purpose specified.

18. The combination of a plurality of carbureter-chambers arranged in a horizontal position, one above another; an air-pipe connecting the rear end of the lower carbureter-chamber with the forward end of the chamber next above; a plurality of carbureting devices arranged transversely in said chambers and forming complete partitions therein; distributors arranged over the said carbureting devices and resting thereon; and connections for delivering the liquid hydrocarbon from the upper carbureter-chambers to the distributors of the chambers next below, for the purpose specified.

19. The combination of a plurality of carbureter-chambers arranged in series in a horizontal position, the lower portions of said chambers being adapted to serve as liquid-reservoirs; air connections for the rear end of each carbureter-chamber to the forward end of the chamber next in series; a plurality of carbureting devices having carbureting-screens of textile fabric arranged transversely in said chambers and forming complete partitions therein, the said carbureting devices being arranged in forwardly-inclined positions; distributors arranged over the said carbureting devices and resting thereon; and means for delivering the liquid hydrocarbon to said distributors, for the purpose specified.

20. The combination of a plurality of carbureter-chambers arranged in series in a horizontal position, the lower portions of said chambers being adapted to serve as liquid-reservoirs; air connections for the rear end of each carbureter-chamber to the forward end of the chamber next in series; a plurality of carbureting devices having carbureting-screens of textile fabric arranged transversely in said chambers and forming complete partitions therein; distributors arranged over the said carbureting devices and resting thereon; and means for delivering the liquid hydrocarbon to said distributors, for the purpose specified.

21. The combination of a plurality of carbureter-chambers arranged in series in a horizontal position; air connections for the rear end of each carbureter-chamber to the forward end of the chamber next in series; a plurality of carbureting devices having carbureting-screens of textile fabric arranged transversely in said chambers and forming complete partitions therein, the said carbureting devices being arranged in forwardly-inclined positions; distributors arranged over the said carbureting devices and resting thereon; and means for delivering the liquid hydrocarbon to said distributors, for the purpose specified.

22. The combination of a plurality of carbureter-chambers arranged in series in a horizontal position; air connections for the rear end of each carbureter-chamber to the forward end of the chamber next in series; a plurality of carbureting devices having carbureting-screens of textile fabric arranged transversely in said chambers and forming complete partitions therein; distributors arranged over the said carbureting devices and resting thereon; and means for delivering the liquid hydrocarbon to said distributors, for the purpose specified.

23. The combination of a plurality of carbureter-chambers arranged in series in a horizontal position, the lower portions of said chambers being adapted to serve as liquid-reservoirs; air connections for the rear end of each carbureter-chamber to the forward end

of the chamber next in series; a plurality of carbureting devices arranged transversely in said chambers and forming complete partitions therein; distributors arranged over the 5 said carbureting devices and resting thereon; and means for delivering the liquid hydrocarbon to said distributors, for the purpose specified.

24. The combination of a plurality of carbureter-chambers arranged in series in a horizontal position; air connections for the rear end of each carbureter-chamber to the forward end of the chamber next in series; a plurality of carbureting devices arranged transversely in said chambers and forming complete partitions therein; distributors arranged over the 15 said carbureting devices and resting thereon; and means for delivering the liquid hydrocarbon to said distributors, for the purpose specified.

25. The combination of a carbureter-chamber arranged in a horizontal position, the lower portion of said chamber being adapted to serve as a liquid-hydrocarbon 25 reservoir; a plurality of carbureting devices consisting of frames having carbureting-screens of textile fabric secured thereon; holders for said carbureting devices arranged in pairs in a forwardly-inclined position on 30 the side walls of said carbureter-chamber; a liquid-hydrocarbon-delivery trough arranged above said carbureting devices; and a distributor adapted to receive the liquid from 35 said delivery-trough resting upon the upper edges of said carbureting devices, for the purpose specified.

26. The combination of a carbureter-chamber arranged in a horizontal position, the lower portion of said chamber being 40 adapted to serve as a liquid-hydrocarbon reservoir; a plurality of carbureting devices consisting of frames having carbureting-screens of textile fabric; holders for said carbureting devices arranged in pairs in a forwardly-inclined position on the side walls of 45 said carbureter-chamber; a liquid-hydrocarbon-delivery trough arranged above said carbureting devices; and a distributor adapted to receive the liquid from 50 said delivery-trough resting upon the upper edges of said carbureting devices, for the purpose specified.

27. The combination of a carbureter-chamber arranged in a horizontal position, the lower portion of said chamber being adapt-

55 ed to serve as a liquid-hydrocarbon reservoir; a plurality of carbureting devices consisting of frames having carbureting-screens of textile fabric secured thereon; holders for said carbureting devices arranged in pairs in a forwardly-inclined position on the side walls of 60 said carbureter-chamber; and a liquid-hydrocarbon-delivery trough arranged above said carbureting devices, for the purpose specified.

28. The combination of a carbureter-chamber arranged in a horizontal position; a

plurality of carbureting devices consisting of frames having carbureting-screens of textile fabric secured thereon; holders for said carbureting devices arranged in pairs in a forwardly-inclined position on the side walls of 70 said carbureter-chamber; a liquid-hydrocarbon-delivery trough arranged above said carbureting devices; and a distributor adapted to receive the liquid from said delivery-trough resting upon the upper edges of said carbureting devices, for the purpose specified. 75

29. The combination of a carbureter-chamber arranged in a horizontal position; a plurality of carbureting devices consisting of frames having carbureting-screens of textile fabric; holders for said carbureting devices arranged in pairs in a forwardly-inclined position on the side walls of said carbureter-chamber; a liquid-hydrocarbon-delivery trough arranged above said carbureting devices; and a distributor adapted to receive the liquid from said delivery-trough resting upon the upper edges of said carbureting devices, for the purpose specified. 80

30. The combination of a carbureter-chamber arranged in a horizontal position, the lower portion of said chamber being adapted to serve as a liquid-reservoir; a plurality of carbureting devices consisting of frames having carbureting-screens of textile fabric secured 95 thereon, arranged transversely in said chamber, forming complete partitions therein, said carbureting devices being inclined forwardly; a liquid-hydrocarbon-delivery trough arranged above said carbureting devices; and a distributor adapted to receive the liquid from the said delivery-trough arranged over the 100 said carbureting devices, for the purpose specified.

31. The combination of a carbureter-chamber arranged in a horizontal position, the lower portion of said chamber being adapted to serve as a liquid-reservoir; a plurality of carbureting devices consisting of frames having carbureting-screens of textile 105 fabric secured thereon, arranged transversely in said chamber, forming complete partitions therein; said liquid-hydrocarbon-delivery trough arranged above said carbureting devices; and a distributor adapted to receive the liquid from the said delivery-trough arranged over the 110 said carbureting devices, for the purpose specified.

32. The combination of a carbureter-chamber arranged in a horizontal position, the lower portion of said chamber being adapted to serve as a liquid-reservoir; a plurality of carbureting devices having carbureting-screens of textile fabric arranged transversely in said chamber, forming complete partitions therein, said carbureting devices being inclined forwardly; a liquid-hydrocarbon-delivery trough arranged above 125 said carbureting devices; and a distributor adapted to receive the liquid from the said 130 carbureting devices.

delivery-trough arranged over the said carbureting devices, for the purpose specified.

33. The combination of a carbureter-chamber arranged in a horizontal position, the lower portion of said chamber being adapted to serve as a liquid-reservoir; a plurality of carbureting devices having carbureting-screens of textile fabric arranged transversely in said chamber, forming complete partitions therein; a liquid-hydrocarbon-delivery trough arranged above said carbureting devices; and a distributer adapted to receive the liquid from the said delivery-trough arranged over the said carbureting devices, for the purpose specified.

34. The combination of a carbureter-chamber arranged in a horizontal position; a plurality of carbureting devices consisting of frames having carbureting-screens of textile fabric secured thereon, arranged transversely in said chamber, forming complete partitions therein, said carbureting devices being inclined forwardly; a liquid-hydrocarbon-delivery trough arranged above said carbureting devices; and a distributer adapted to receive the liquid from the said delivery-trough arranged over the said carbureting devices, for the purpose specified.

35. The combination of a carbureter-chamber arranged in a horizontal position; a plurality of carbureting devices consisting of frames having carbureting-screens of textile fabric secured thereon, arranged transversely in said chamber, forming complete partitions therein; a liquid-hydrocarbon-delivery trough arranged above said carbureting devices; and a distributer adapted to receive the liquid from the said delivery-trough arranged over the said carbureting devices, for the purpose specified.

36. The combination of a carbureter-chamber arranged in a horizontal position; a plurality of carbureting devices having carbureting-screens of textile fabric arranged transversely in said chamber, forming complete partitions therein; a liquid-hydrocarbon-delivery trough arranged above said carbureting devices.

bureting devices; and a distributer adapted to receive the liquid from the said delivery-trough arranged over the said carbureting devices, for the purpose specified.

37. The combination of a carbureter-chamber arranged in a horizontal position, the lower portion of said chamber being adapted to serve as a liquid-reservoir; a plurality of carbureting devices arranged transversely in said chamber, forming complete partitions therein and depending into said reservoir; a liquid-hydrocarbon-delivery trough arranged above said carbureting devices; and a distributer adapted to receive the liquid from the said delivery-trough arranged over the said carbureting devices, for the purpose specified.

38. The combination of a carbureter-chamber arranged in a horizontal position, the lower portion of said chamber being adapted to serve as a liquid-reservoir; a plurality of carbureting devices arranged transversely in said chamber, forming complete partitions therein and depending into said reservoir; a liquid-hydrocarbon-delivery trough arranged above said carbureting devices; and a distributer adapted to receive the liquid from the said delivery-trough arranged over the said carbureting devices, for the purpose specified.

39. The combination of a carbureter-chamber, the lower portion of said chamber being adapted to serve as a liquid-hydrocarbon reservoir; a plurality of carbureting devices arranged in said chamber having their lower edges extending into the said liquid-reservoir; a distributer of fibrous material arranged upon said carbureting devices; and means for supplying liquid hydrocarbon to said distributer, for the purpose specified.

In witness whereof I have hereunto set my hand and seal in presence of two witnesses.

HERBERT A. BURCH. [L. S.]
